(57) **CLAIM**

The ornamental design for forklift, as shown and described.

DESCRIPTION

FIG. 1 is a perspective view of the forklift;

FIG. 2 is a front view of the forklift;

FIG. 3 is a rear view of the forklift;

FIG. 4 is a left side view of the forklift;

FIG. 5 is a right side view of the forklift;

FIG. 6 is a top view of the forklift; and,

FIG. 7 is a bottom view of the forklift.

The broken lines shown in the figures are included for the purpose of illustrating portions of the forklift which form no part of the claimed design.

1 Claim, 7 Drawing Sheets

FIG. 1

FIG. 2

FIG. 3

FIG. 4

FIG. 5

FIG. 6

FIG. 7
